(57) **CLAIM**

The ornamental design for a cable tie tool as shown and described.

DESCRIPTION

FIG. 1 is a front perspective view of a cable tie tool of our new design.

FIG. 2 is a left side view of the cable tie tool of FIG. 1, the right side view being a mirror image thereof.

FIG. 3 is a top view of the cable tie tool of FIG. 1.

FIG. 4 is a bottom view of the cable tie tool of FIG. 1.

FIG. 5 is a rear view of the cable tie tool of FIG. 1; and, FIG. 6 is a front view of the cable tie tool of FIG. 1.

1 Claim, 6 Drawing Sheets
